UNITED STATES PATENT OFFICE.

WILLIAM F. HARVEY, OF TORONTO, ONTARIO, CANADA.

DISPENSING CARTON.

Application filed March 13, 1925. Serial No. 15,289.

The principal objects of the invention are, to provide a carton, particularly for holding cereals or other foods or materials which it is desirable to protect from contact with the atmosphere and from dust.

A further object is to provide an opening in the carton which will enable the ready dispensing of the contents and which may be readily closed.

10 The principal feature of the invention consists in providing an opening at one corner of the carton to allow of the dispensing of the contents, a portion of the box being temporarily opened and being provided with means for securely holding the separated portion in position to close the opening.

In the drawings, Figure 1 is a perspective view of a carton to which the present invention is applied.

Figure 2 is a perspective view showing the corner opened up for dispensing.

Figure 3 is a perspective view showing the corner replaced to close the opening.

25 Figure 4 is a reduced plan view of the blank from which the carton is made.

In the packaging of cereal such as corn flakes, bran, etc. and many other classes of granular or powdered foods or materials, it is extremely desirable that means be provided for the dispensing of small portions of the contents and then closing the carton to maintain the contents free from contact with the air in ordinary circulation and to prevent the settling of dust upon the materials contained therein.

30 In order to accomplish this result I have designed a carton in which a substantial opening may be made in one corner in such a manner that the portion of the carton may be temporarily removed and then replaced to effectively close the opening.

This is accomplished by scoring lightly or marking the front face of the package at the upper edge and a distance below the upper edge according to the width of opening desired and for the desired length back from the corner where the edges of the cardboard overlap.

35 The front 1 of the carton is folded inwardly at the top and the upper marking line 2 is arranged close to the crease or bend 3.

The side 4 of the carton overlaps the in-turned edge 5 of the front and the marking

6 continues from the marking 2 to meet a vertical line of penetrating score marks or perforations 7 in the end portion 4.

A lower line 8 is spaced the desired depth down from the top of the box and meets the vertical penetrating score marks 7. Lines 2, 6 and 8 are each preferably formed by scoring deeply in a continuous line so that the walls of the box are almost severed, or they may be formed by puncturing or perforating the walls with a series of short score marks arranged in alignment so that the lines so formed may be broken through readily. The pressure of the fingers against the line 7 of penetrating score marks then separates the material of the box along this line and the breaking of the cardboard may be continued either with the fingers or with a knife along the score lines 2, 6 and 8 and the portion thus freed may be swung open as illustrated in Figure 2.

In forming the carton the seaming flap 5 is cut in toward the box at the upper end and a double tab 10 is formed.

The outer side strip 4 has a narrow 40 gummed strip 11 which adheres to the strip 5 close to the angle bend but the inner portion, including the double tab is free.

The penetrating score marks 7 in the strip 4 are arranged at the inward edge of the gummed strip 11 and prior to opening the box the base of the adjacent tabs 10 serves to seal the perforations made by the penetrating score marks 7 and when the line 7 is broken through, the double tab 10 will break away clear.

The closure member A may be of any desirable size according to the class of material contained in the carton and when the desired quantity of material has been dispensed at any one time through the opening, the opening may be very effectively closed by simply swinging the member back into position.

The double tab 10 then forms the means for holding the member A in position to close the opening, the split of the tab receiving the edge of the side 4 of the box in the manner illustrated in Figure 3.

The box is thus effectively closed to prevent the ingress of dust or of moisture, such as frequently found in kitchen atmospheres that will detrimentally affect the contents of the carton.

Goods contained in a carton such as de-

scribed will be kept in a sanitary condition, free from contamination and will be readily accessible.

What I claim as my invention is:—

- 5 1. A dispensing carton having a portion of the front and side wall separable to form a dispensing opening, said side wall portion having a divided end adapted to grip the outer wall of the box to hold the separated portion in place to close the opening.
- 10 2. A dispensing carton having a narrow strip connected with the front wall and overlapped by the side wall, said strip having its upper end divided to form free tabs, a row of vertical perforations in the side wall extending transversely of the base of said tabs, and perforations extending horizontally therefrom to enable the freeing of a portion to form an opening.
- 15 3. A dispensing carton having the blank

- 25
- 30
- 35

formed with side strips adapted to overlap, one of said side strips having a gummed portion and the other strip being adapted to extend past said gummed portion and forming a pair of free tabs therebeyond, score marks formed in said latter strip adjacent to said tabs and score marks in the other side strip and in the adjoining front panel, all of said score marks being so arranged as to form a separable member having the aforesaid tabs secured to and extending therefrom.

4. A dispensing carton having a portion at the upper corner scored horizontally around the corner to form a separable strip extending around the corner, said strip having its extremity divided in the form of a pair of tabs and extending beneath the outer side panel of the box.

WILLIAM F. HARVEY.
